UNITED STATES PATENT OFFICE.

GEORGE HILGER, OF CHICAGO, ILLINOIS.

REFRIGERATION SYSTEM.

Application filed April 30, 1926. Serial No. 105,619.

The present invention relates to improvements in refrigeration systems and has more particular reference to the so-called spray systems wherein a cooling liquid is sprayed or atomized into the air in one chamber to cool the air and to induce circulation thereof into an adjacent storage chamber.

One object of the present invention is to provide a new and improved spray refrigeration system for use in large cold storage rooms and the like whereby the food products contained in such rooms may be refrigerated efficiently and without shrinkage or danger of deterioration or spoiling due to the deposition of moisture or brine on them.

Another object of the invention is to provide a spray refrigeration system having a novel cooling means for removing the moisture from the spray-cooled air, which means includes a coil through which the cooling liquid is passed before it is sprayed into the air in the cooling chamber.

Other objects and advantages of the invention will be apparent from the following description taken in connection with the accompanying drawings, in which

Figure 1 is a sectional view of a cold storage room equipped with a refrigeration system embodying the features of the present invention.

Fig. 2 is a section taken along the line 2—2 of Fig. 1.

Fig. 3 is a fragmentary sectional view of a cold storage room embodying another form of the invention.

While I have shown in the drawings and will herein describe the preferred embodiments of the invention, it is to be understood that I do not intend to be limited thereby to the particular forms disclosed, but aim to cover all modifications and alternative constructions falling within the spirit and scope of the invention as expressed in the appended claims.

Referring to the exemplary embodiments of the invention, the numerals 10 and 11 represent respectively the top and side walls of a cold storage room which is divided into an upper cooling chamber 12 and a relatively larger chamber 13 for storing food products to be refrigerated. These chambers are defined in the present instance by a partition wall in the form of a shallow tank 14 supported near the ceiling of the room by horizontal cross beams 15. To provide connecting passageways 16 at opposite ends of

the chambers, the tank is made substantially equal in width to the refrigeration room but shorter than the room. The two chambers are thus arranged for the continuous circulation of air through them. A suitable pan 17 may be suspended from the beams 15 to catch the drippings from the tank.

Brine or other suitable cooling liquid may be used for spraying in the system, this being contained and cooled in the tank 14 in the present instance. In the embodiment of the invention shown in Fig. 1, cooling of the liquid in the tank is effected by a coiled pipe 18 having its inlet end 19 and its outlet end 20 connected to an outside source of refrigerating agent such as the ordinary compression type unit employing ammonia or other refrigerant. Preferably the inlet portion of the refrigerating coil is disposed above one end of the tank and in the path of the air flowing out of the chamber 12. The remainder of the coil is positioned below the level of the liquid in the tank. Since the refrigerant flows through the exposed portion of the coil and then through the immersed portion, the former will always be maintained at a temperature somewhat below that of the liquid in the tank.

To mix the cooling liquid intimately with the air in the chamber 12 and thereby cool the air quickly and efficiently, the liquid is drawn from the tank and sprayed or atomized into the air. This may be accomplished by one or more nozzles 21 positioned above the tank preferably near the inlet end of the cooling chamber and supplied with liquid under pressure by a suitable power-driven pump 22 having its intake connected with the tank outlet pipe 23. To induce slow continuous circulation of the spray-cooled air, the nozzles are arranged to direct the spray longitudinally of the chamber. Thus, the air cooled by the spray will be forced downwardly into the storage chamber 13 at one end of the room and warm air from the storage chamber will be drawn into the cooling chamber at the other end of the room.

Most of the cooling liquid introduced into the air by the nozzles falls back into the tank to be cooled and used over again. Some of the liquid, however, may be carried forward with the cooled air either in the form of water vapor or as a fog of minute particles which may remain suspended in the air. To prevent any of the liquid thus

carried by the air from being deposited on the food products in the storage chamber, means is provided for removing it before the cooled air leaves the cooling chamber.

5 One means employed for this purpose comprises a series of parallel baffle plates 24 extending across the cooling chamber in the path of the spray-cooled air. These plates provide large cold surfaces upon which part 10 of the suspended particles of liquid will collect thereby being removed from the air.

The exposed portion of the refrigerating coil 18 constitutes a secondary means for dehydrating the spray-cooled air. As the 15 air passes into the cooling zone surrounding the coil, its temperature is reduced, such further cooling of the air causing the suspended particles of moisture or brine which may have escaped precipitation in the baffle 20 plates to unite forming large drops which will settle out quickly falling directly into the tank or becoming deposited upon the surface of the coil. Owing to this further cooling of the air, a portion of its water 25 vapor is also condensed at this point, which condensation further assists in the coagulation of the liquid suspended or mechanically held in the air by forming small particles which unite with the suspended spray particles. It will be apparent that the combined effect of the baffles and the condensing coil 18 is to remove all of the suspended particles of liquid which otherwise would be carried into the storage chamber. The 30 baffles serve as a primary precipitating means while the condensing coil removes any particles which are not removed in the baffles.

Other means may be provided for further 40 cooling the spray-cooled air. For example, in the form of the invention shown in Fig. 3, the cooling liquid itself is used for this purpose. To this end a coiled pipe 25 is mounted in the path of the spray-cooled air, 45 one end of the pipe being connected with a pressure pump 26 arranged to draw the cooling liquid from the tank 14 and force the liquid through the coiled pipe. The other end of the coil leads to spray nozzles 27 50 at the opposite end of the spray chamber. Since the cooling liquid passing through the coiled pipe 25 will always be somewhat colder than the air cooled by the spray, further cooling of the spray-cooled air will be 55 effected which will serve to precipitate moisture or brine carried forward with the circulating air and escaping precipitation in the baffle plates. It will be apparent that the coil 25 functions in the same way as the 60 refrigerating coil 18 shown in Fig. 1.

The arrangement just described has particular utility in systems where ice is used to refrigerate the cooling liquid or where the liquid is cooled at some point outside of 65 the refrigeration room. Fig. 3 illustrates

the use of a system employing ice as the refrigerating agent, the blocks 28 being immersed in the liquid in the tank. Suitable means (not shown) may be provided to carry away the overflow liquid resulting 70 from melting of the ice.

With the system of refrigeration which I have provided, it will be apparent the air enters the storage chamber in a saturated condition and substantially free from moisture or brine mechanically held. Since the air in the storage chamber is always warmer than the incoming air, there is no danger of any moisture or brine carried by the air being deposited on the food products. Furthermore, inasmuch as the incoming air is saturated, the degree of saturation of the air surrounding the food products will always be relatively high. Shrinkage of the food products due to evaporation of moisture 85 contained in them will, therefore, be effectively avoided.

I claim as my invention:

1. A cold storage room having, in combination, a partition wall dividing the room 90 into upper and lower chambers, said wall being shorter than said room whereby to provide connecting passageways between opposite ends of said chambers, means for containing a supply of cooling liquid, refrigerating means to cool said liquid, means operable to mix said liquid with the air in said upper chamber, said mixing means being located near the inlet end of said upper chamber, a coiled pipe positioned 95 near the outlet end of said upper chamber, and means operable to supply said liquid to said coil and then to deliver the liquid to said mixing means.

2. A refrigeration system comprising, in combination, means providing cooling and storage chambers connected at their opposite ends, a coiled pipe positioned near the outlet end of said cooling chamber, a nozzle connected to one end of said coiled pipe and 110 positioned near the inlet of said cooling chamber, a source of cooling liquid, and means to pump the liquid from said source through said coil and then deliver the liquid 115 to said nozzle.

3. A refrigeration system having, in combination, a cooling chamber arranged for the circulation of air therethrough, a source of cooling liquid, a condensing means and a spray nozzle located in said chamber, and a 120 pump operable to pass said cooling liquid through said condensing means and then deliver the liquid to said nozzle.

4. A refrigeration system having, in combination, means providing a cooling chamber, a nozzle and a coiled pipe positioned at opposite ends of said chamber, means for containing a cooling liquid, and means to pump the liquid through said coil to said nozzle.

5. A refrigeration system having, in combination, means providing a cooling chamber arranged for the free circulation of air therethrough, a tank in said chamber adapted to contain a liquid to be cooled, a coil positioned above said tank near the outlet end of said chamber, a nozzle arranged in the inlet end of said chamber and directed toward said coil, and a pump to draw said liquid from

10 said tank and deliver it to said nozzle through said coil.

6. A refrigeration system having, in combination, means providing a cooling chamber, a spray nozzle arranged to discharge liquid longitudinally of said chamber to cool the air in the chamber and to induce circulation of the air, a condenser positioned in the path of the cooled air, a source of cooling liquid, and means for passing said liquid

20 through said condenser and said nozzle under pressure.

7. A refrigeration system having, in com-

bination, means providing a cooling chamber, a coiled pipe positioned near the outlet end of said chamber, a source of cooled liquid, a nozzle near the inlet end of said chamber arranged to discharge liquid toward said coil, said nozzle being connected with one end of the coil, and means to supply said liquid under pressure to the other end

25 30

8. A refrigeration system having, in combination, a chamber arranged for the circulation of air therethrough, a pipe line, a source of cooling liquid, means to supply said liquid to one end of said line, means at the discharge end of said line to mix said liquid with the air in said chamber whereby to cool the air, and a condensing means interposed in said line in the path of the cooled

35 40

air.

In testimony whereof, I have hereunto affixed my signature.

GEORGE HILGER.
